DESIGN FOR A LINK FOR BRACELETS AND THE LIKE

Nathan D. Wyckoff, Chicago, Ill.

Application October 25, 1945, Serial No. 123,165

Term of patent 3½ years

(Cl. D45—4)

To all whom it may concern:

Be it known that I, Nathan D. Wyckoff, a citizen of the United States, residing at Chicago, in the county of Cook and State of Illinois, have invented a new, original, and ornamental Design for a Link for Bracelets and the like, of which the following is a specification, reference being made to the accompanying drawing, forming a part thereof and in which:

Fig. 1 is a front elevational view of a link embodying my new design;

Fig. 2 is a longitudinal sectional view of a link; and

Fig. 3 is an enlarged fragmentary view showing one longitudinal portion of the link.

I claim:

The ornamental design for a link for bracelets and the like, as shown.

NATHAN D. WYCKOFF.
